UNITED STATES PATENT OFFICE.

JENNINGS GRANT AMBROSE, OF SAN DIEGO, CALIFORNIA.

AIRSHIP.

1,291,354.

Specification of Letters Patent. Patented Jan. 14, 1919.

Application filed September 23, 1918. Serial No. 255,364.

To all whom it may concern:

Be it known that I, JENNINGS GRANT AMBROSE, a citizen of the United States, residing at San Diego, in the county of San Diego and State of California, have invented a new and useful Airship, of which the following is a specification.

This invention relates to airships, one of the objects being to provide an airship having a novel arrangement of lifting wheels or helicopters combined therewith adjacent the center of gravity for assisting in maintaining the airship at a desired elevation while in flight, there being means combined with the said wheels for preventing the machine from being turned out of its course by the action of the wheels when elevating the machine.

Another object is to so locate the helicopters that they will not interfere with the soaring action of the machine.

A still further object is to provide a machine in which the body constitutes a sustaining plane.

Another object is to so locate the weight of the machine below the center that, when the machine is in flight, it will be balanced and there will be no danger of it descending out of control end first.

With the foregoing and other objects in view which will appear as the description proceeds, the invention consists of certain novel details of construction and combinations of parts which will be hereinafter more fully described and pointed out in the claim, it being understood that various changes may be made in the construction and arrangement of the parts without departing from the spirit or sacrificing any of the advantages of the invention as set forth in the appended claim.

In the accompanying drawings the preferred form of the invention has been shown.

In said drawings—

Figure 1 is a view partly in side elevation and partly in longitudinal section through a machine embodying the present improvements.

Fig. 2 is a plan view of the propelling mechanism.

Fig. 3 is a plan view of the complete machine.

Referring to the figures by characters of reference, 1 designates the elongated body of the airship which can be of any proportions desired and is provided with any suit-

able running gear 2. The bottom of the body is flat to constitute a sustaining plane and erected above and connected to the body at suitable points are sustaining planes 3 and 4 preferably arranged as shown with two superposed planes 3 in front of a single sustaining plane 4. Rudders are arranged at the tail end of the body as shown at 5 and may be controlled in any manner desired, as by means of a steering wheel 6.

Extending through the body 1 from top to bottom thereof and at right angles to the longitudinal axis of the body are flues 7 in the upper end of each of which is arranged a helicopter or lifting wheel 8 secured to the upper end of a shaft 9 journaled in bearings 10 at the center of the flue. Each shaft is adapted to receive motion through gears 11 from a shaft 12 which extends into the space between the flues and is driven through chain and sprocket mechanism 13 from the shaft 14 of an engine 15. The shafts of both lifting wheels are driven by the engine in the same manner and any suitable arrangement of clutches may be provided for coupling or uncoupling either or both of the shafts 12 to the engine. It is not deemed necessary to show or describe the clutches as they merely constitute old structures forming no part of the present invention.

Chain and sprocket mechanism indicated at 16 may be employed for transmitting motion from the engine shaft to a shaft 17 extending forward and adapted to drive through gears 18, vertical shaft 19, and gears 20, the shaft 21 of a propeller 22. Any suitable form of clutch, not shown, can be employed for controlling the actuation of the propeller and this clutch, as well as the other clutches in the machine, can be controlled by one of a series of levers 23.

Arranged within the flues are fins 24 so pitched that when air is forced downwardly within the flues by the rotating wheels 8, the pressure thereof against the fins will offset the tendency of the machine to rotate out of its course. These fins are particularly useful where only one flue and one wheel 8 are employed, and which modified arrangement can be employed in small machines.

It will be noted that the engine and body are located below the planes 3 and 4. The machine is thus stabilized while in flight and is prevented from falling end first, should control of the machine be lost.

While one engine has been referred to, it

is to be understood that this term is to be considered broadly as a driving unit and can consist of one or more motors connected together or, if preferred, operating independently as shown, for example, in Fig 2.

What is claimed is:—

An airship including a body having a flat bottom and a winglike curved top constituting a sustaining plane, flues extending 10 through the body from top to bottom thereof, an engine between the flues, a lifting wheel within the upper portion of each flue,

a propeller, means driven by the engine for actuating either or both the wheels and the propeller, and sustaining planes above the 15 body and in front and back of the flues.

In testimony that I claim the foregoing as my own, I have hereto affixed my signature in the presence of two witnesses.

JENNINGS GRANT AMBROSE.
